GUNNAR JENSEN, OF SWISSVALE, PENNSYLVANIA, ASSIGNOR TO WESTINGHOUSE ELECTRIC AND MANUFACTURING COMPANY, A CORPORATION OF PENNSYLVANIA.

CONNECTER.

Application filed November 3, 1919. Serial No. 335,304.

My invention relates to electrical connectors and particularly to connectors for use in systems employing potentials and currents of relatively high values.

One object of my invention is to provide a device of the above indicated character that shall facilitate the connection and disconnection of electrical conductors.

Another object of my invention is to provide a connector, of the resilient-clamp type, that shall be suitable for systems having potentials and currents of relatively high values, and be of substantially minimum size.

Another object of my invention is to provide a readily-operable safety connector, for relatively high values of current and voltage, that may be freely manipulated by an operator, with his bare hands without danger of injury from the connector.

A further object of my invention is to provide a connector adapted to effectively receive and position one or more conductors of various sizes.

Heretofore, certain spring-clamp connectors have been used in systems employing currents and voltages of relatively low values and, to the best of my knowledge, these have usually been constructed chiefly for mechanical effectiveness and to provide good contact bearing surfaces. Attempts have been made, in certain of these connectors, to provide insulating coverings or other means to lessen the likelihood of shock or injury to an operator, but the uncertainty of the life of the covering materials sometimes causes them to increase the hazard rather than afford a safeguard.

Readily-removable spring-clamp connectors have been considered impracticable above certain limits of current and voltage. For the higher values, the rigid or permanent type of connector has been employed which is difficult to manipulate and dangerous to an operator, unless handled with extreme care. For handling this type of connector, rubber gloves have been employed but, as in the case of the above mentioned connector coverings, the uncertainty of the life and construction of gloves is such an element of danger to an operator that their use, in certain places, has been prohibited.

In practicing my invention, I provide a readily-operable connector, the composition, form and relation of the elements of which

are such as to provide a device of substantially maximum potential resistive strength and minimum size. The device may be freely handled by an operator while the conductors connected by it are energized, 60 thus effecting a saving of time, removing the element of danger and facilitating the operations of conducting an experiment or a test where temporary connections and unsafe potentials are employed.

Figure 1 of the accompanying drawings is a plan view of a high-potential connector embodying my invention; Fig. 2 is a side sectional view of the same; Fig. 3 is an end elevational view thereof and Fig. 4 is a 70 fragmentary view, similar to a portion of Fig. 2, showing an adaptation of the device to a conductor of smaller diameter than that shown in Fig. 2.

In general, my device comprises an insulating body member 1, a tubular conducting member 2, a plunger rod or gripping member 3 and an operating handle or walking beam 4 that is pivotally mounted on the member 1 and is assisted in actuating 80 the rod 3 by springs 5 and 6.

The member 1 is preferably formed as a single integral mass of fibrous material, such as shredded canvas that is impregnated with a binder, such as a phenolic condensation product and dried. Subsequently, the material is placed in a suitable mold and subjected to heat and pressure to compact the material and harden the binder. This material is unaffected by wide temperature 90 changes, moisture, oils, weak acids and alkalis.

The member 1 comprises a tubular portion 7 having relatively-thick walls to provide high puncture strength, an end wall 8, 95 and side walls 9, all of which are designed with a view not only to the mechanical strength and protection of the structure therein but to creepage distances which are vital in high-potential service.

The member 2 is shorter than the portion 7 and may be placed at an intermediate position therein during or after the molding process. This provides creepage surface and is a measure of protection to an 105 operator, in that he may not easily come into contact with the member 2. Screws 10, extending through the walls of the portion 7 and the member 2, secure a sleeve 11 110 in one end of the member 2. The sleeve 11

is interchangeable with other similar sleeves and provides means for positioning one conductor 12, or conductors of various sizes, concentrically in the member 2. This connection may be of a permanent nature, after it has been decided which conductor is to be utilized, but may be changed if desired.

Raised tubular portions 13 on the member 1 provide creepage distance around the screws 10 and means for receiving a quantity of cement 14 or other material to insulate the screws from the member 4 and the spring 6. Openings 15 in the member 4 permit access to the screws 10.

The rod 3 is relatively heavy and thick, of material such as steel, to provide durability and strength as well as a sufficient bearing area at its end 16 that is serrated or scarred by cutting narrow slots of V-shape at right angles to each other. This provides a biting surface comprising a plurality of hard, sharp pyramids or points 17 and, as electrical conductors are usually of copper, holds the latter securely.

When in engagement with a conductor 18 of medium or relatively large diameter, a sufficient number of the points 17 will engage the conductor to hold it securely. To assist in holding a smaller conductor 18, Fig. 4, that may be engaged by a relatively small number of the points 17, a countersunk portion 19 is provided in the inner surface of the member 2 opposite the rod 3. This forms a kink in the conductor 18 that, in co-operation with the rod 3 and the edges of the portion 19, is held securely in position. The portion 19 is relatively shallow to provide backing for, and prevent breakage of, the small conductors that are bent into the portion 19 during the bending action.

The outer end of the rod 3 is provided with a head portion 20 having a rounded outer surface and between which and the member 1 the helical compression spring 5, embracing the rod 3, exerts a force tending to move the rod away from the conductor 18. This permits the removal of the rod 3 from the bore of the member 2 to permit the unobstructed insertion therein of the conductor 18 and opposes the force of the spring 6. The spring 6 is considerably stronger than the spring 5 and thereby supplies the actuating force to clamp the rod 3 against the conductor 18. This force being inversely proportional to the size of the conductor, since the spring 5 will be in greater compression when the conductor is small, is automatically graduated in accordance with the size of the conductor to be held. This provides relatively great forces for large conductors and sufficient forces which are less likely to injure small conductors.

The walking beam 4, preferably con-

structed of relatively thin sheet metal, is pressed or bent to channel shape having intermediate perforate bearing portions 21 for a cross pin 22 extending between the side walls 9, sloping side walls 23 and an inwardly curved end portion 24 that serves as a stop member to engage the member 1, to assist the walls 8, 9 and 23 in enclosing the space between the beam 4 and the member 1 and to present a smooth rounded edge 75 to the hand of an operator.

A button or member 25 of relatively hard and durable insulating material, preferably similar to the material of the member 1, has a reduced portion 26 fitting an aperture 80 in the beam 4 and a smooth rounded surface 27 engaging the head 20 of the rod 3. The member 25 may be secured by cement or other means or be loosely seated in position.

The spring 6 embraces the pin 22 and has tangentially-projecting portions 28 and 29 bearing against the beam 4 and the member 1, respectively. The walls 9 are thicker at the portions 30 to provide good bearing surfaces and support for the pin 22 and slope from the portions 30 to substantially the end of the member 1 in order to permit the member 4 to be depressed freely by an operator.

By my invention, I provide a spring-clamp connector in which the movable clamping member travels in a straight-line path at right angles to the conductor to be clamped, whereby the clamping force is evenly applied over a relatively-wide surface, to ensure maximum clamping efficiency.

Many points, as mentioned, have been taken into consideration to provide a connector suitable for very high voltages that is safe, effective, rugged and durable, that permits latitude as to the matter of the service in which it may be employed and that may be quickly and easily manipulated.

A device of substantially the construction, material and dimensions shown in the drawings, has operated satisfactorily and will operate continuously while carrying 500 amperes at potentials up to 7000 volts. A connector for other values of current and voltage may be constructed in accordance with the principles herein explained, that will be suitable for convenient hand manipulation.

While I have shown and described a particular form of my invention, changes may be effected therein without departing from the spirit and scope thereof, as set forth in the appended claims.

I claim as my invention:

1. A connector comprising a body member of molded insulating material having tubular and channel portions, a hollow metal member in the tubular portion and extend-

- ing between points removed from the ends thereof, said metal member having a countersunk portion in its inner surface, an interchangeable sleeve for securing a conductor concentrically in one end of said metal member, a longitudinally-movable metal rod having a serrated end, said rod being disposed at right angles to said metal member opposite the countersunk portion, a spring biasing 5 said rod away from said metal member, a walking beam, a pin supporting said walking beam, an insulating member disposed on said walking beam and engaging said rod, a spring embracing said pin and having 10 portions pressing against said beam and said body member to oppose said first spring, screws to hold said sleeve in position, and bodies of insulating material sealing the ends of said screws, said beam having openings opposite said screws.
2. A connector comprising a body member of molded insulating material having tubular and projecting portions, a hollow metal member disposed in the tubular portion and having a countersunk portion in its inner surface, means for securing a conductor to said metal member, a movable rod extending through the walls of said tubular portion and said metal member opposite said countersunk portion, means biasing said rod outwardly, a member pivoted on the projecting portions, and means causing said pivoted member to oppose said outwardly biasing means.
3. A connector comprising a body member of molded insulating material having a tubular portion and a channel portion parallel thereto, said channel portion being closed at one end, a conducting sleeve within the tubular portion for receiving the terminals of conductors, a clamp member partially located in said channel portion and means for actuating said clamp member to grip a conductor terminal.
4. A connector for conductors comprising a member having a longitudinally extending channel portion and a side aperture, a conducting sleeve within the member for receiving the terminals of conductors, a clamping member disposed at right angles to the first member and extending through said aperture and having one end for engaging a conductor terminal and the other end projecting into the channel, and an operating lever device substantially closing the channel and 55 yieldingly retaining the clamping member in operative retaining engagement with the conductor.
5. A connector for conductors comprising a member having a longitudinally extending channel portion and a side aperture, a conducting sleeve within the member for receiving the terminals of conductors, a clamping member disposed at right angles to the first member and having one end for engaging a conductor terminal and the other end projecting through said aperture into the channel, a spring for normally retracting the clamping member, and an operating member device for normally yieldingly retaining the clamp member in operative retaining engagement with the conductor, the said operating member device being pivoted in the channel and substantially closing the latter.
6. A connector for conductors comprising a tubular insulating member having a side aperture, a conducting sleeve within the tubular member for receiving the terminals of the conductors, a clamping means mounted on the insulating member and extending through said aperture for engaging and retaining the terminal of a conductor within the said sleeve, yielding means for withdrawing the clamping means from engagement with the conductor, and a lever device for normally yieldingly pressing the clamping means into engagement with the terminal of the conductor.

In testimony whereof, I have hereunto subscribed my name this 27th day of October, 1919.

G. JENSEN.
